UNITED STATES PATENT OFFICE.

OSCAR L. SAVITZ, OF ALLENTOWN, PENNSYLVANIA, ASSIGNOR OF ONE-THIRD TO
EDWIN S. RABENOLD AND ONE-THIRD TO HARVEY E. WINK, BOTH OF ALLEN-
TOWN, PENNSYLVANIA.

ARTIFICIAL FOOT.

1,160,112.

Specification of Letters Patent.

Patented Nov. 9, 1915.

Application filed July 7, 1915. Serial No. 38,465.

To all whom it may concern:

Be it known that I, OSCAR L. SAVITZ, a citizen of the United States, residing at Allentown, in the county of Lehigh and State of Pennsylvania, have invented new and useful Improvements in Artificial Feet, of which the following is a specification.

My invention relates to improvements in artificial limbs, and its object is to provide 10 an artificial limb which affords a free and easy foot motion, and which embodies novel means for securing an efficient pneumatic cushioning action.

The invention consists of the features of 15 construction, combination and arrangement of parts herein fully described and claimed, reference being had to the accompanying drawing in which:—

Figure 1 is a vertical front to rear section 20 through an artificial limb embodying my invention. Fig. 2 is a vertical transverse section on the line 2—2 of Fig. 1. Fig. 3 is a vertical transverse section on the line 3—3 of Fig. 1.

Referring to the drawing, 1 designates the 25 leg section of the limb, which may be made of metal or other suitable material, and 2 designates the foot section of the limb, which is preferably made of elastic material, 30 such as rubber, but may be made of a composite structure designed to afford the necessary flexibility for the cushioning actions, as hereinafter set forth.

As shown, the leg section 1 is provided 35 at its upper portion with a stump receiving socket 3, which may be provided with any suitable soft lining. As shown in the present instance, this socket comprises outer and inner walls 4 and 5 spaced to provide a 40 cushioning chamber 6, the inner wall 5 is preferably made of some suitable soft flexible or elastic material and is yieldingly backed by air contained in the chamber 6 so that a cushioning action will be obtained 45 to prevent objectionable chafing or rubbing of the stump and to adapt it to receive the thrust from the artificial limb during the walking action without producing soreness or other discomfort. A valve filling tube 7 50 is provided whereby the chamber 6 may be supplied with air whenever required.

The leg section 1 is provided with a base portion 8 which fits within the foot section

2, which foot section is formed with a chamber 3 to receive the said base of the leg section. The foot section is provided with lugs 9 at opposite sides thereof and in rear of the instep line for pivotal connection with rods or braces 10 carried by the leg section, whereby an articulating connection is provided. Jointed to the foot section in rear of the articulating connection is a rod 11 movable in a guide member 12 on the leg section and controlled by an interposed spring 13, by which the limb sections are 65 maintained in a proper relative position and the articulating motion of the said sections upon one another properly cushioned.

In accordance with my invention the foot section 2 is provided with a pair of superposed air chambers 14 and 15, the air chamber 14 being separated from the receiving chamber 3 by a flexible diaphragm 16, in which diaphragm the chamber 15 is formed, the chamber 14 is closed against communication with the atmosphere except through a valved tube or conductor 17, while the chamber 15 communicates with the atmosphere at the front and rear of the foot section, as indicated at 18 and 19, respectively. 70 The chamber 14 is adapted to be supplied with air whenever required, which air is retained in said chamber for a cushioning action, air being only furnished at sufficient intervals to compensate for that lost by 75 leakage. The chamber 15 on the other end is adapted to be supplied with air by suction and to have the air exhausted therefrom by compression, the suction being produced by the collapse of its walls when the 80 limb is in action by the tread pressure, for the exhaust of the air and the production of a partial vacuum for the admission of fresh air when the walls expand or dilate upon the removal of pressure, as when the 85 foot is raised.

It will thus be understood that in addition to the elastic action afforded by the foot section itself, the tread portion of the foot is permitted to have resiliency through the 100 medium of the air cushion 14, while the upper portion of the foot section to which the leg section is connected, namely the wall or diaphragm 15, is also permitted to have a yielding action, by means of which the action of the limb in walking is cushioned and 105

objectionable jars, pressures or strains upon the stump of the natural limb prevented.

I claim:

- An artificial limb including a leg section and a foot section connected for articulating motion, said foot section being formed of elastic material and having an air chamber therein disposed between its upper and lower surfaces, the upper surface of said foot section forming a yielding wall or diaphragm

and having an air passage therethrough, said diaphragm forming the support for the leg section, and means for supplying air to said air chamber.

In testimony whereof I affix my signature 15 in presence of two witnesses.

OSCAR L. SAVITZ.
